UNITED STATES PATENT OFFICE

PAUL A. KETCHPEL, OF PITTSBURGH, PENNSYLVANIA, ASSIGNOR, BY MESNE ASSIGNMENTS, TO THE STANDARD STOKER COMPANY, INCORPORATED, A CORPORATION OF DELAWARE

LOCOMOTIVE STOKER

Application filed August 4, 1928. Serial No. 297,408.

This invention relates to mechanical stokers for locomotives of the type that transfer the fuel from the tender to the fire box through the lower part of the fire door opening by screw conveyors.

One object of this invention is the provision of a compact stoker in a locomotive that takes up very little room in the locomotive cab.

Another object of the invention is to position the means for elevating the coal from the conveying unit to the fire door opening on an incline so that the coal will pass from the top end of the elevating conduit enclosing said means to the distributing device with less packing than occurs in stokers where the path of the coal changes its direction at an abrupt angle.

Other objects and advantages of the invention will appear from the following description and appended claim, taken in connection with the accompanying drawings, in which Fig. 1 is a sectional view taken on the center line of a portion of a locomotive and tender, showing the invention as applied theron, with parts in vertical section and some parts broken away.

Fig. 2 is a plan view of the stoker, with the boiler back head in section at the fire door opening.

Fig. 3 is a sectional view of the tender and stoker trough, taken on line 3-3 of Fig. 2, illustrating the sealing angle support and coal crusher.

Fig. 4 is a sectional view of part of the tender and trough of the stoker, taken on line 4-4 of Fig. 3.

Fig. 5 is a sectional view of the fire box at the fire door opening, taken on the line 5-5 of Fig. 1, and illustrating the distributing apparatus.

Fig. 6 is a sectional view taken on the line 6-6 of Fig. 2 illustrating the integrally cast gear case and engine body.

Fig. 7 is a vertical section taken on line 7-7 of Fig. 5 with the distributing plate 8 removed illustrating how the upper end of the elevating conduit is supported at the fire door.

In Fig. 1 the numeral 1 represents the trough of the stoker which is movably

mounted in the tender and swings laterally when the engine and tender are rounding curves and crossing switches. Coal falls by gravity from the coal bunker 19 into the trough 1, where a conveyor screw 2 moves it forward. The larger lumps are reduced to a size suitable for proper firing by the screw 2 forcing them against the crusher 3, described in detail hereafter. Then the coal is conveyed forward from the crusher to the end of the conveyor screw 2 where it is transferred to an inclined screw 4, rotating in a sloping conduit 5 which is fixed on the locomotive frame 6, and conveyed to the fire door opening 7 and deposited on a plate 8, from which it falls onto a jet table 9 having fluid jets 10 under pressure for distributing the fuel evenly to all parts of the fire bed.

The stoker is driven by an engine 15 located in the tender of the locomotive and which is novel in construction. The speed reducing gear box 16 is cast integral with the engine and has driving connections 17 and 18 to the front and rear of the stoker. A flexible shaft extends forward from the connection 17 and drives the inclined screw 4 and a longer flexible shaft extends rearward and drives the conveyor screw 2, as described more in detail later.

The stoker conveyor trough 1 is supported under the coal bunker 19 in a compartment or cut-out 20 in the tank as shown on Fig. 3, by the feet 21 resting on angle irons 22 which are secured to the side walls 23 of the tank cut-out. The feet 21 are made sufficiently long to hold the trough central between the sides 23 of the tank cut-out 20. The trough is flexibly connected with the locomotive unit of the stoker by a ball joint 24 which allows the trough to move vertically or laterally with respect to the center line of the locomotive. When moving laterally the trough is held central at the trough support 25 as already explained, and when moving vertically, the feet 21 rock on the angle irons 22. Since the ball joint 24 holds the trough rigid to the unit on the locomotive with respect to end wise movement any variation in the distance between the locomotive and

tender causes the trough feet 21 to slide back and forth on the angle irons 22.

The floor of the tender is provided with slide plates which are well known in the art and designated here by numerals 31 and 32. When slide plate 31 is pulled forward, coal falls by gravity from the coal bunker 19 into the trough 1. To prevent the leakage of coal from the sides of the trough, especially when the locomotive is on a curve and the center line of the trough 1 is not parallel with the center line of the tender, a sealing angle 34 is provided. The sealing angle 34 is supported by clips 35 riveted to the floor of the tender and spaced to allow ample freedom for the sealing angle to move laterally with the trough. Thus the coal is allowed to drop into the trough and be conveyed therethrough without any spilling.

As the coal usually supplied in the coal bunker 19 is of the run-of-mine grade, an improved crusher is here shown in Figures 3 and 4. As the coal falls into the trough 1 from the coal bunker 19 it is advanced forwardly against the spool shaped crusher 3 having teeth 38, and reduced to the proper size for efficient firing.

This crusher 3 is mounted rotatably in journals 39 extending inwardly from the side walls 40 of the conveyor trough. The shafts 45 are rigidly mounted in the hub of the crusher and turn freely in the journals 39. The crusher is of a cylindrical type having its central section concaved to more nearly surround the conveying screw 2 which cooperates with it in crushing the coal. The periphery of the crusher may be provided with spiral teeth as commonly found on cylindrical crushers or may be provided with spike teeth or spurs as shown at 38.

In the operation of this combination of a cylindrical crusher 3 and the spiral screw 2 set at substantially right angles thereto, the coal is crushed with less power than required by a screw forcing the coal directly against a toothed plate commonly used in stokers, because of the greater crushing force gained by the toggle effect which the crusher has, due to its rotating and crushing the medium size lumps of coal between its lower portion and the hub of the screw 2.

In other words, the coal being carried forward by the conveyor screw 2 presses against the rear lower portion of the crusher and, as the coal is carried through, the crusher is caused to rotate and thus break any excessive lumps of coal to a size most adaptable for economic firing. Coal small enough to need no further breaking passes under the crusher about the hub of the screw, at the bottom of the trough. In case of a clog, due to iron or other foreign substances lodging between the screw 2 and the crusher 3 its removal is facilitated by being able to insert a bar in the holes 47 provided in the flange 48 at

the side of the crusher and rotate the crusher backwards.

The forward end of the screw 2 extends a short distance beyond the ball 49 on the forward end of the trough (Fig. 1) and is slightly converging in diameter to allow lateral motion of the conveyor trough without binding the end of the screw in the casting 50 fixed on the locomotive frame 6. This screw 2 is purposely extended to deliver the coal from the crusher to the inclined screw 4 without packing and undue abrasion. Such construction is advantageous because if the ball joint was positioned closer to the screw 4 it would necessitate lowering the gear case 56 which would in many locomotives interfere with the locomotive frame and make installations difficult.

The inclined screw 4 conveys the coal to the fire door opening and has provided at its lower end a double flight 51 to pick up the coal quickly and further prevent the coal from packing at the end of the conveyor screw. It is also provided with a double flight 52 at its upper end to give a uniform discharge at the outlet end of the elevator conduit. The screw is housed in a sloping conduit 5 as shown here comprising a base casting 50 supported on the locomotive frame and a casting 54 seating in the fire door frame, the two castings being connected by the tube 55. However, it should be understood that the whole conduit may be formed of a single casting if desired. The base casting has legs 60 provided for bolting it rigidly to the locomotive frame 6. It is preferred to take care of the expansion of the boiler between the casting 54 and the fire door frame 62. In Fig. 5 and Fig. 7 the casting 54 is shown supported by the inward extensions 63 of the fire door frame 62. This casting 54 slides on the fire door frame 62 and is set back from the back head as shown in Fig. 7 at 64 to allow telescopic action between the casting 54 and the fire door frame 62, to take care of the boiler expansion and contraction.

The casting 54 has a detachable cover 65 and its removal allows ready access to the fire box for making repairs or inspection of the boiler.

The sloping conduit 5 has been set on a substantial angle with the back head to allow the coal to pass to the distributor plate with only a slight change in its direction. That is, a screw more nearly horizontal will require less forcing action to move the coal from the top of the conduit to the distributing plate 66, which naturally results in delivering the coal with little abrasion and pulverizing, keeping the stack losses at a minimum and accomplishing one of the objects of this invention. In stokers where the coal is brought up in a conduit substantially parallel with the back head there is considerable force required to deliver the coal

to the distributor jets because the coal must be forced from the side of the screw instead of the end or forced around an elbow if the screw does not extend to the top. This causes 5 excessive abrasion and a considerable quantity of fine coal is pulverized, which goes out of the locomotive stack unburned. In this stoker, it is possible to have the jets 10 positioned forward of the inside surface of the 10 fire box backhead and be able to distribute the coal entirely by the action of the fluid jets 10 to all areas of the fire box, whereas others require the jets set rather close to the screw to prevent packing and must fire coal to the 15 rear areas of the fire box by the use of deflecting ribs mounted on the distributor plate inside of the fire box.

The casting 54 and its cover 65 are so shaped as to change the body of the coal from 20 a circular to a rectangular cross section and provide an increasing area for the coal to move through without any packing. Such construction takes up very little of the fire door opening and is desirable for cleaning the 25 fire.

The distributor plate 66, consisting of the jet table 9 and the receiving portion 8, resting on the boiler in the fire door opening, is hooked under the casting 54 to hold it in 30 place and is capable of being removed very easily. It will be noted that a space 67 exists below the distributor plate to allow the cold air to be drawn in by the locomotive draft to cool the plate and prevent its burning away.

The surface 8 is inclined downwardly as it extends into the fire box, allowing the force of gravity to assist in moving the coal to the jet table 9. As the coal is delivered to the portion 8 it falls upon the jet table 9 40 and is distributed by the jets 10 under pressure to all areas of the fire bed.

The jet table 9 is inclined upwardly to secure more range with less power than would be required if the table were set horizontal. 45 Thus the front portion of long fire boxes may be fired with a very short jet plate.

As shown on Fig. 5 there are two cored passages 68 and 69 which communicate respectively with the steam pipes 70 and 71 50 and the jets 10. The cored passages are located at the sides of the distributor plate instead of beneath it to allow the plate to be set as low as possible. The pipes 70 and 71 are provided with valve connections, not 55 shown here, with which the fireman may vary the jet pressure and govern the amount of coal supplied to either side of the fire bed.

In Fig. 1 and Fig. 2 the means of driving the stoker is clearly shown. The engine 15 60 is preferably located on the tender and thereby accomplishes one of the objects of this invention. The trend of the present day to equip the rear of the locomotive with locomotive boosters and other like power devices to 65 gain greater driving power makes it neces-

sary to limit the weight and size of the stoker apparatus; therefore it is preferred to mount the driving unit on the tender as here shown.

As shown in Fig. 6, the body of the engine 15 is cast integral with the speed reducing gear case 16. Due to the small space available on either the locomotive or the tender, this is a feature that will allow many installations where a separate gear box and engine would be prohibitive because of its greater 75 size.

In Fig. 6, a cross section through the engine 15, and the gear case 16 illustrates the pistons 78 and the cross heads 79, the crankshaft 80 and the worm 81 and the worm wheel 82. 80 The crank shaft 80 is mounted in the engine through the opening covered by the bearing 83 after which the connection rods 84 are assembled on the crank shaft; access being gained through the opening closed by the 85 crank case 85. The worm is splined on a continuation of the crank shaft turned down to press into the hub of the worm, and the worm wheel 82 is mounted in the gear case through the opening in the side wall closed by the 90 gear case cover 86.

The worm wheel shaft 87 carries driving connections to the front and rear of the stoker. At the front, a flexible shaft 75 is connected 95 through universal joints to helical pinion shaft 88, journaled in a case below the casting 50 and carrying a pinion 89 which is mounted to mesh with a helical gear 90 keyed on an extension of the hub of the inclined screw 4. Thus an efficient and compact and lubricated means for driving the inclined screw is provided that does not in any way interfere with the transfer of the coal from one screw to the other.

From the rear driving connection 18 of the gear case 16 a flexible shaft 95 is connected through universal joints to a pinion shaft extending from the gear box 96 at the rear of the conveyor trough 1 and drives the conveying screw 2 through gearing provided in the gear box.

From the foregoing it will be apparent that I have invented a stoker that is very compact, simple and efficient in operation, composed of few moving parts, economical to manufacture, and one that can readily be installed upon locomotives.

I claim as my invention:

In combination, a furnace provided with a firebox having an upstanding wall with a firing opening therein, a fuel bin for said furnace, a feed conduit extending between said bin and said firing opening comprising a transfer section located beneath the floor of the bin and a single inclined elevator section 120 communicating in end to end relation with and extending upwardly and forwardly from the front end of said transfer section to the lower portion of said firing opening, said transfer section and elevator section being 125 130

- rigid with respect to one another at their junction, the upper forward end of the elevator section opening endwise directly into said lower portion of the firing opening, pressure fluid distributing means arranged adjacent the lower portion of said firing opening to receive fuel from the upper end of said elevator section, a screw conveyor in said transfer section and a separate screw conveyor in said elevator section, the screw in said transfer section being driven from its end remote from the screw in said elevator section, which last named screw is driven from its lower end, and means for driving the screw in said elevator section including a shaft fixed with the screw and extending downwardly and rearwardly through the bottom wall of the transfer section to a point exterior thereof.
- 20 In testimony whereof, I affix my signature.
PAUL A. KETCHPEL.
